HANKSCRAFT COMPANY, A CORPORATION OF WISCONSIN.

LIQUID-CONDUCTOR HEATER DEVICE.

Application filed October 1, 1923. Serial No. 665,761.

Our invention relates to liquid-conductor heating devices and it has particular relation to electrodes embodied therein.

Heretofore, liquid-conductor heating devices have been designed and successfully operated, by employing chemically treated electrodes or by employing untreated electrodes and utilizing water having suitable electrical conductivity, either initially or by reason of suitable treatment. In some instances, devices of the character above indicated have become inoperative or unreliable because of impairment of the electrodes through loss of the chemical substances which they originally possessed or because of unsuitability of the liquid conductor.

This invention provides means for ensuring reliable operation and long life for liquid-conductor heating devices without chemical treatment of the electrodes or of the water through which the current flows.

Electric current, passing through a liquid in sufficient amount to vaporize it, materially alters its conductivity, because the vapor forms in bubbles which may permeate the whole or a part of the liquid carrying the current and thus tend to force it away from the electrodes and to transform the original homogeneous body into a cellular structure of far less conductivity per unit volume, thus causing a decrease of current at constant potential.

Unless specific means are employed for avoiding or counteracting the above-mentioned condition, a marked decrease in current results, or, if a voltage sufficient to maintain a current of a desired amount is applied to ensure satisfactory vaporization, an undesirably high current will flow during the early part of the operation. Furthermore, if there is a gradual decrease in current, as the liquid boils away, it will not shut off sharply to zero, as is desirable in cases where the apparatus is so designed as to automatically cut off the heating effect upon boiling away of the liquid.

One of the objects of our invention is to provide a liquid-conductor heating device adapted for the utilization of non-treated electrodes and ordinary tap water.

Another object of our invention is to provide a liquid-conductor heating device hav-

ing a substantially constant and relatively low resistance, thereby producing proper vaporization.

A further object of our invention is to provide a liquid-conductor heating device having electrodes of such construction, as to permit the escape of bubbles that are formed in the liquid when heated by current flowing therethrough.

A still further object of our invention is to provide a liquid-conductor heating device having a plurality of electrodes and a liquid therebetween for the purpose of regulating the duration of current flow and for heating, through vaporization of the liquid between the electrodes, the electrodes being adapted to permit the escape of bubbles formed in the liquid when heated by the current flowing therethrough, being designed in such manner that the active area of the electrodes in contact with the conducting liquid is increased when bubbles are formed by the passage of current.

In the accompanying drawings:

Figure 1 is a vertical, sectional view of a milk warmer embodying our invention;

Fig. 2 is a top plan view of the device shown in Fig. 1, the milk bottle being removed, and a portion of the upper electrode being partially broken away for clearness.

Fig. 3 is an enlarged fragmentary sectional view of the upper electrode shown in Fig. 1.

Fig. 4 is a vertical sectional view of a device embodying a modification of our invention.

Fig. 5 is a top plan view of a pair of electrodes of modified structure constructed in accordance with our invention.

Fig. 6 is also a top plan view of another pair of electrodes embodying another modified structure.

Fig. 7 is a vertical sectional view of an electrode embodying a still further modified structure.

Fig. 8 is a top plan view of an electrode embodying another modified structure.

Fig. 9 is a plan view of an electrode embodying a further modification, and

Fig. 10 is a sectional view of the bottom portion of vessel and its electrodes, one of which is like that shown in Fig. 9.

In Figs. 1 and 2 of the drawings, we have

shown our invention embodied in a baby-milk-warmer which comprises a receptacle 1 of non-conducting material, preferably porcelain, having a main chamber 2 adapted to receive a bottle 3, the contents of which are to be heated, and an auxiliary chamber 4 in open communication with the main chamber 2. The chamber 4 is adapted to receive a liquid-measuring device 5 for determining the quantity of liquid required for heating various quantities of milk.

As indicated in Figs. 1 and 2 of the drawings, the measuring device 5 has a bottom opening which, before insertion of the device in the chamber 4, is closed by a gravity-operated valve, shown in Fig. 1 as a ball. When the device is seated in the chamber 4, the bottom wall of the latter will unseat the valve and thus permit the liquid to flow from the device into the main chamber.

The chamber 2 is provided with a pair of spaced-apart electrodes 6 and 7 in the bottom thereof, and is adapted to contain a vaporizable body of liquid 8 for the purpose of making circuit-closing contact with the electrodes 6 and 7. The electrode 6 is of the disk type and is disposed in a depression 9 in the porcelain receptacle 1 and may be provided with a current-conducting screw 11 to serve as a terminal for an electric conductor 12. Located in the center of the depression 9 is another depression 13 that is centered with an opening 14 in which the screw 11 is located. A suitable packing material 15 may be placed in the depression 13 under the head of the screw 11 for the purpose of providing a liquid-tight seal. The electrode 6 may also be provided with a plurality of openings 16 to receive raised portions 17 that are located in the depression 9.

The raised portions 17 of porcelain are provided for insulating the electrode 6 from a plurality of current-carrying terminals 18. The terminals 18 are connected to a ring 19 that is, in turn, connected to an electric conductor 21 for the purpose of transmitting electric current to the electrode 7.

The electrode 7 is of disk type and has one or more openings 22 therein for the purpose of permitting bubbles to escape when the liquid is heated by electric current flowing through it. The openings in the electrode 7, when a plurality are provided, are spaced in such manner as to provide an unbroken ring 23 for the purpose of insuring positive contact with the terminals 18. The electrode 7 may be held in operative position by gravity or otherwise, if desired and, preferably, its edge is provided with a non-conducting coating 24, shown in enlarged detail in Fig. 3, for preventing a short circuit in case it accidentally engages the electrode 6 in the operation of insertion or removal. The coating 24 may extend over any desired portion of the upper electrode, or, the protective

insulation for preventing short circuit may be on any portion of the lower electrode or incorporated in the container. The insulation may also be on the edges of the perforations so that a conductor accidentally dropped through a perforation and coming in contact with the lower electrode would not come in contact with the upper electrode and thus cause a short circuit.

A circular plate 25 may be mounted on the under side of the receptacle for the purpose of enclosing the terminals thereof and may be held in position by an insulating nut 26 that co-operates with the extended portion of the screw 11.

Referring to Fig. 4, a modification of our invention is illustrated in which a receptacle 27, having a body of vaporizable liquid 28 disposed therein, serves as one of the electrodes of the apparatus and is provided with a terminal connection 29. The receptacle 27 may have a cover member 31 and an inner electrode 32, also of dish-shape construction, disposed therein. The electrode 32 may have an opening or a plurality of openings 33 in the bottom thereof to permit the escape of bubbles, though, with electrodes of this form, such openings are not essential since, when bubbles are formed within the liquid, a marked increase of active area of the electrodes is produced. The electrode is provided with a centrally disposed, conical pocket 34 in the base thereof to engage a terminal 35 that is correspondingly tapered at its upper end.

The terminal 35 may be insulated from the receptacle 27 by a non-conducting bushing 36. The outer face of the electrode 32 may be provided with a plurality of non-conducting spacers 37 for the purpose of insulating the electrode 32 from the receptacle electrode 27.

A modified electrode structure, as shown in Fig. 5, comprises two interlaced spiral electrodes 38 and 39, respectively. The electrodes 38 and 39 may be held in spaced relation by suitable insulating members 41. The spiral passages 42 between the electrodes 38 and 39 permit bubbles to escape therethrough.

Another modified electrode structure, as shown in Fig. 6, comprises two grid-type electrodes 43 and 44 that are held in spaced relation by suitable insulating members 45, the proportion of active electrode surface to the area of gas relief remaining such as to permit the ready escape of bubbles.

The electrode 46, shown in Fig. 7, has a plurality of depending portions 47 on the under side thereof, some of which have conical depressions 48 therein to receive terminal posts (not shown).

The electrode 49, as shown in Fig. 8, is constructed of wire mesh 51 and, preferably, is provided with a non-conducting rim 52.

Bubbles are permitted to escape through the openings 53.

In the modification shown in Figs. 9 and 10, the receptacle 1 and the lower electrode 5 are, or may be, like the corresponding parts previously shown and described but the upper electrode 54 is provided with a lug or ear 55 that makes contact with the head of a terminal bolt 56. The electrode is provided with insulating buttons 57 to rest upon the lower electrode. All or portions of the electrode edge may be provided with insulation, as indicated at 58, and the upper surface may be entirely coated, if desired.

15 In practising our invention, we provide a ready release for vapor in order to minimize the average vapor content of the bubble structure, or we utilize the expansion of volume of the bubble structure to bring into 20 activity sufficient additional areas of electrodes so that the resulting total conductivity is not undesirably decreased by the bubble formation.

25 Area in excess of that which would be necessary to carry a current through liquid alone is given to the electrodes, they being in such positions that the desired operation is ensured by a small amount of liquid.

The various electrodes shown and described are only a few of many electrode structures that may be employed and, consequently, it is to be understood that the specific disclosures are not to be regarded as limiting our invention to specific forms, 15 dimensions or relative location of the essential elements, except insofar as limitations are necessary to ensure satisfactory operation and desired results, in view of which only such limitations may properly be imposed as are set forth in the appended claims.

The apparatus disclosed in the present application, including the perforated electrode or other means for effecting a rapid 15 dissipation of energy, is claimed broadly in our co-pending application Serial No. 1,784, filed January 12, 1925.

We claim as our invention:

1. An electric heating or cooking apparatus comprising a receptacle for a body of vaporizable liquid and two superposed and spaced-apart electrodes adapted for normal circuit-closing contact with said liquid, the upper electrode being held in position by gravity only and having a non-conducting rim.

2. An electric heating or cooking apparatus comprising a vessel adapted to con-

tain a body of vaporizable liquid and a pair of superposed perforated electrodes in the bottom part of said vessel, the upper electrode being held in position by gravity only.

3. An electric heating or cooking apparatus comprising a receptacle adapted to contain a body of vaporizable liquid and a pair of superposed, spaced-apart electrodes in the bottom of said receptacle, the upper electrode being perforated and having a non-conducting rim and being held in operative position by gravity only.

4. An electric heating apparatus comprising a receptacle for vaporizable liquid having a main chamber containing a pair of superposed and spaced-apart electrodes, the upper electrode having one or more perforations, and an auxiliary chamber in open communication with said main chamber to receive a liquid-measuring device which automatically discharges its contents into the main chamber when placed in the auxiliary chamber.

5. An electric heating or cooking apparatus comprising a receptacle for a body of vaporizable liquid and a pair of spaced-apart electrodes in the bottom of said receptacle, at least one of said electrodes being constructed to permit the escape of bubbles, a plurality of current-conducting supports adapted for engagement with the upper electrode, said electrode being held in operative position by gravity only and having at least a portion of its outer peripheral surface coated with a non-conducting material to prevent a short circuit upon accidental engagement with the lower electrode.

6. An electric heating or cooking apparatus comprising a receptacle for a body of vaporizable liquid and a plurality of spaced-apart electrodes for making normal circuit-closing contact with said liquid, said electrodes being constructed to permit the escape of bubbles, and measuring means co-operating with said receptacle to determine the amount of liquid required for operation thereof.

7. An electric heating or cooking apparatus comprising a liquid-containing vessel constituting an electrode and a perforated electrode supported in said vessel in spaced relation to the bottom thereof and held in position by gravity.

In testimony whereof, we have hereunto subscribed our names this 17th day of September, 1923.

MARSHALL W. HANKS.
